REGULATING APPARATUS

James W. Armour and L. V. Andrews, Worcester,
Mass., assignors to Riley Stoker Corporation,
Worcester, Mass., a corporation of Massachusetts

Application March 7, 1934, Serial No. 714,539

9 Claims. (Cl. 171—242)

This invention relates to regulating apparatus, and more particularly to a construction suitable for controlling the flow of an electric current in a desired manner.

5 It is one object of the invention to provide a regulating apparatus which will be simple and inexpensive to manufacture, and which will make possible an accurate control of an electric current.

10 It is a further object of the invention to provide a regulating apparatus which can be actuated either automatically or manually, and particularly to so construct the apparatus as to permit a manual adjustment without disconnecting the automatic mechanism.

15 It is a further object of the invention to provide a regulating apparatus which is so constructed that the automatic mechanism cannot apply an excessive force thereto, however the manual adjustment may be set.

20 It is a further object of the invention to provide a regulating apparatus which may be conveniently mounted on a vertical panel with most of the apparatus concealed behind the panel.

25 With these and other objects in view, as will be apparent to those skilled in the art, the invention resides in the combination of parts set forth in the specification and covered by the claims appended hereto.

30 Referring to the drawing illustrating one embodiment of the invention, and in which like reference numerals indicate like parts,

Fig. 1 is a front elevation of a regulating apparatus;

Fig. 2 is a section on the line 2—2 of Fig. 1;

35 Fig. 3 is a section on the line 3—3 of Fig. 2;

Fig. 4 is a rear elevation of the regulating apparatus; and

Fig. 5 is a perspective view of a removable pole-piece cap.

40 In the drawing we have shown a regulating apparatus adapted to vary the impedance in an alternating current circuit, this being accomplished by varying the reactance of the circuit, but it will be apparent that certain features of 45 the invention are applicable to the control of direct currents as well.

The embodiment illustrated comprises an annular coil 11 adapted for connection to an electric circuit, and an iron core 12 axially adjustable 50 within the coil to vary the reactance thereof. A C-shaped iron member 14 is mounted with its end portions adjacent the ends of the core 12, this member 14 forming a return path for the magnetic flux produced by the current in the coil. 55 By thus concentrating the flux in a definite path,

a greatly increased operating range is obtained. The core 12 and member 14 are preferably of laminated construction to avoid eddy current losses.

5 In order to support the various parts, we preferably utilize a vertical panel 15 to the rear face of which there is secured a frame 16. The member 14 is fastened to the top of the frame 16 between the coil and the panel. The core 12 is slidably supported in spaced upper and lower guides 18, which are channel-shaped in transverse cross-section and face each other, as shown in Fig. 2. The guides 18 extend through the coil 11 to support the same, and they in turn are supported by the member 14. These guides are preferably of brass or other non-magnetic material to facilitate the sliding of the core thereon. By spacing the guides from each other we avoid providing a path for the circulation of induced currents.

10 Means is preferably provided to permit manual actuation of the core 12 from the front of the panel 15, while at the same time indicating to the operator the position of the core. For this purpose an indicator plate 20 is mounted on the front of the panel, and a horizontal rotatable 15 shaft 21 is provided which extends rearwardly through the plate 20, panel 15, and frame 16. An operating handle 23 is fastened to the front 20 end of the shaft 21 by means of a set-screw 24,

25 and a pointer or indicator 26 is formed integral 30 with the handle and arranged to cooperate with markings 27 located in a circular arc on the plate 20. A wheel 29 is mounted on the shaft 21 in the rear of the frame 16, this wheel being provided with spokes 30 and a central hub 31 which 35 is fastened to the shaft by means of a set-screw 32. The wheel 29 serves as a crank which is operatively joined to the slidable core 12 by means of a connecting rod 34. To one end of the connecting rod there is fastened a pin 35 40 which extends through a lug 36 (Fig. 3) welded or otherwise secured to the core 12. The other end of the connecting rod is pivoted to one of the spokes 30 by means of a screw 38 and a flanged sleeve 39 (Fig. 2). Several openings 40 45 are provided in the spoke at different distances from the axis of the wheel. The screw 38 can be inserted through any of these openings to vary the extent of travel of the core. The pin 35 is adjustable in a longitudinal slot 42 (Fig. 4) in 50 the connecting rod, so that the core can be positioned as desired relative to the connecting rod.

55 In order that the core may be held in a fixed position of adjustment when desired, we provide a horizontal rotatable shaft 44 which extends 55

through the plate 20, panel 15, and frame 16. A knurled knob 45 is secured to the front end of the shaft to facilitate manual rotation thereof, and the rear portion of the shaft is screw-threaded to receive a nut 46. The wheel 29 is provided with a flange 47 which is located between the nut 46 and the frame 16. The wheel prevents rotation of the nut, so that when the shaft 44 is turned in one direction by means of the knob 45 10 the nut will clamp the flange 47 against the frame 16 and prevent rotation of the wheel.

In many cases it is desirable to control the position of the core 12 automatically, and for this purpose we have illustrated diagrammatically an 15 automatic regulator 50 (Fig. 4). This regulator may be of any suitable type adapted to respond to changes in pressure, temperature, fluid flow, liquid level, or any other variable desired. Ordinarily the variable which controls the regulator 20 will also be affected by a change in the impedance of the coil 11. For example, if the coil 11 were connected in a circuit with a mechanism for supplying fuel to a steam boiler furnace at a controlled rate, the regulator 50 would usually be arranged to respond to variations in the pressure 25 of the steam, or perhaps to changes in the temperature of a building heated by the boiler. The regulator 50 is preferably arranged to actuate the core 12 through the medium of a frictional driving 30 connection, so that the core can be adjusted manually at any time independently of the regulator or relative thereto, and yet no matter how the parts are adjusted it will be impossible for the regulator to apply excessive and dangerous forces. 35 For this purpose we have shown a member 51 rotatably mounted on the rear portion of the shaft 21 and held in place by a washer 53 and cotter pin 54. This member 51 is provided with a radially projecting arm 56 which is joined to the automatic regulator 50 by means of a connecting rod 57. The member 51 is also provided with two opposite radial projections 59 having hollow ends in which are slidably mounted friction shoes 60. These shoes are urged outwardly against the inner surface of the wheel 29 by means of coiled 45 compression springs 61.

The arm 56 is provided with an opening 63 which is spaced from the axis of the shaft 21 a distance equal to the distance between the axes of 50 the shafts 21 and 44. If no automatic regulator is to be used, the arm 56 may be moved to bring the opening 63 into line with the shaft 44, so that the shaft may be inserted through the opening. This will hold the member 51 fixed, and the friction 55 of the shoes 60 will prevent accidental movement of the wheel 29 while allowing manual adjustment thereof by means of the handle 23.

Our improved regulating apparatus is adapted 60 to control feeders of the electro-magnetic vibrating type, some of which have a single magnet coil and others of which have two magnet coils connected in parallel. We provide means, in addition to the adjustment of the core 12, whereby the impedance of the coil 11 may be decreased when 65 the regulating apparatus is to be used with a double-coil feeder. For this purpose we utilize an iron block or cap 65 which forms a part of the return path for the magnetic flux, this block being readily removable to provide an air gap in said path when desired. In the embodiment illustrated the block 65 is located between the member 14 and the core guides 18, being held in place 70 by clips 66 (Fig. 4) secured to the guides and to 75 the member 14. The removable block 65 is

formed with two spaced vertical ribs 67 which engage the member 14 and hold the block against movement in a direction parallel to the core 12. The block 65 is comparatively thin, and it is elongated horizontally to provide an extensive area 5 adjacent to the core 12 for the passage of the magnetic flux between these parts.

The operation of the invention will now be apparent from the above disclosure. The automatic regulator 50 acts through the connecting 10 rod 57, member 51 and friction shoes 60 to control the position of the wheel 29, and this in turn acts through the connecting rod 34 to control the position of the slidable core 12. As the core 12 is moved relative to the coil 11, the impedance of the 15 coil will vary, and the current flow through any suitable device connected to the coil will be controlled. The pointer 25 will indicate the position of the core at all times. The position of the core relative to the automatic regulator can be 20 changed manually as desired by turning the handle 23, thus causing the wheel 29 to slip on the shoes 60. The wheel can be locked in a stationary position at any time by turning the knob 45, thus causing the nut 46 to clamp the flange 25 47 against the frame 16. Under these conditions the regulator 50 can continue to operate, and the shoes 60 will slip on the wheel. If during automatic operation the core 12 reaches its travel limit 30 ahead of the regulator 50, no damage can occur, since the shoes will slip before an excessive force is applied. In case no automatic regulator is to be used, the member 51 can be held fixed by passing the rod 44 through the opening 63, and the friction shoes will serve to hold the wheel in any 35 desired position of manual adjustment. By removing the block 65, the impedance of the coil 11 for a given position of the core 12 will be greatly decreased, so that the coil will allow more current to flow therethrough, and the apparatus can 40 be used to control, for example, a feeder having double capacity.

Our improved regulating apparatus is simple 45 and inexpensive to manufacture, and thoroughly reliable in operation. Only such parts are visible in front of the panel as are used for manual operation and for indicating purposes, and the construction is particularly suitable for use in connection with other devices to form a complete combustion control system. 50

Having thus described our invention, what we claim as new and desire to secure by Letters Patent is:

1. Regulating apparatus comprising an annular 55 electrical coil, a core axially slidable through the coil to vary the reactance thereof, and an iron member arranged with its ends adjacent to the ends of the core to form a return path for the magnetic flux, said member having a portion which may be readily removed to produce an air gap in the return path and thus decrease the 60 reactance of the coil.

2. Regulating apparatus comprising an annular 65 electrical coil, a core axially slidable through the coil to vary the reactance thereof, and a C-shaped iron member arranged with its ends adjacent to the ends of the core to form a return path for the magnetic flux, one end portion of said member being enlarged to provide an increased area for 70 flux transmission, said end portion being readily removable to decrease the reactance of the coil when desired.

3. Regulating apparatus comprising means 75 providing a path for the flow of an electric cur-

rent, a movable member associated with said means to control the impedance thereof, a manually operable device positively connected to the member to move the same, an automatic regulator, and a frictional driving connection arranged to transmit motion from the automatic regulator to the member.

4. Regulating apparatus comprising means providing a path for the flow of an electric current, a movable member associated with said means to control the impedance thereof, a manually operable device positively connected to the member to move the same, an automatic regulator, a frictional driving connection arranged to transmit motion from the automatic regulator to the member, and manually operable means to lock said member in any desired position of adjustment.

5. Regulating apparatus comprising a vertical panel, a frame mounted on the rear face of the panel, a horizontal shaft journaled in the frame and extending through the panel, an electric conductor mounted on the frame, a movable member associated with the conductor to control the impedance thereof, a positive mechanical connection between the shaft and the member, a handle secured to the front end of the shaft, an automatic regulator, and a frictional driving connection between the automatic regulator and the member.

6. Regulating apparatus comprising a vertical panel, a frame mounted on the rear face of the panel, a horizontal shaft journaled in the frame and extending through the panel, an annular electrical coil mounted on the frame, a core axially slidable through the coil to vary the reactance thereof, a mechanical connection between the shaft and the core to cause sliding of the core as the shaft is turned, an automatic regulator, means providing a frictional driving connection between the regulator and the shaft, and a handle secured to the front end of the shaft.

7. Regulating apparatus comprising a vertical panel, a frame mounted on the rear face of the panel, a horizontal shaft journaled in the frame and extending through the panel, an annular

electrical coil mounted on the frame, a core axially slidable through the coil to vary the reactance thereof, a wheel secured to the shaft in the rear of the panel, a connecting rod joining the wheel to the core, a member pivoted to the shaft adjacent to the wheel, means providing a frictional driving connection between the member and the wheel, an automatic regulator connected to the member to actuate the same, and a handle secured to the front end of the shaft.

8. Regulating apparatus comprising a vertical panel, a frame mounted on the rear face of the panel, a horizontal shaft journaled in the frame and extending through the panel, an annular electrical coil mounted on the frame, a core axially slidable through the coil to vary the reactance thereof, a wheel secured to the shaft in the rear of the panel, a connecting rod joining the wheel to the core, a member pivoted to the shaft adjacent to the wheel, a friction shoe mounted on the member, a spring urging the shoe into frictional engagement with the wheel, an automatic regulator connected to the member to actuate the same, and a handle secured to the front end of the shaft.

9. Regulating apparatus comprising a vertical panel, a frame mounted on the rear face of the panel, a horizontal shaft journaled in the frame and extending through the panel, an annular electrical coil mounted on the frame, a core axially slidable through the coil to vary the reactance thereof, a wheel secured to the shaft in the rear of the panel, a connecting rod joining the wheel to the core, a member pivoted to the shaft adjacent to the wheel, means providing a frictional driving connection between the member and the wheel, an automatic regulator connected to the member to actuate the same, a handle secured to the front end of the shaft, and means operable from in front of the panel whereby the wheel may be locked in a fixed position to cause slipping of the frictional connection as the automatic regulator operates.
